PORTABLE FOLDING STOOL OR SEAT

Clifford D. Keely, West Englewood, N. J.

Application March 17, 1945, Serial No. 583,238

3 Claims. (Cl. 155—149)

1

My present invention relates to improvements in portable folding stools or seats. The object of my invention is a folding stool characterized by lightness, compactness and ease of setting up and knocking down, as well as ease and cheapness of manufacture.

My invention consists in the improved arrangement of parts below described and more specifically pointed out in the appended claims. My invention will be best understood by reference to the following detailed description taken with the annexed drawings, in which

Fig. 1 is a view in isometric perspective of an illustrative embodiment of my improved stool ready for use.

Fig. 2 is a rear view in elevation thereof;

Fig. 3 is a view of same in folded position showing parts in partly extended form;

Fig. 4 is a detail showing a corner of my device when in folded position looking down upon the seat;

Fig. 5 is a view of the folded device as seen from the right of Fig. 3;

Fig. 6 is an enlarged detail showing a preferred universal hinge employed by me;

Fig. 7 is a view in vertical elevation in set up position of a modification;

Fig. 8 is a view of same in partially knocked down position;

Fig. 9 is a view seen sidewise of Fig. 8;

Fig. 10 is an edgewise view as seen from the bottom of Fig. 8 following the next folding operation;

Fig. 11 is a section taken on line 11—11 of Fig. 8 and shows the movement undergone by the seat in going from folded to set-up position.

Referring now to the drawings by characters of reference, more particularly to Figs. 1 to 6, 1 denotes generally the seat proper of the device which may comprise a flat supporting member 2 of plywood or other material and a cushion 3 secured thereto. The support for the seat consists of a flat, generally rectangular (when occupying a single plane) member denoted by 5 which is foldable along a vertical axis $a-a$ and in the embodiment now described, along horizontal axes $b-b$ and $c-c$. In the set-up position of Fig. 1, the folds or panels A and B thus form two sides of a triangular prism, the dihedral angle being desirably in the neighborhood of 90° . When the support 5 is folded along the axis $a-a$ to a dihedral angle of 180° (as in Fig. 8 describing a similar embodiment) it is thus foldable along the axes $b-b$ and $c-c$ as clearly seen in Fig. 3; it being noted that hinges 6, 6 along $b-b$, Fig. 2, work

2

oppositely from hinges 7, 7 along axis $c-c$; whereas hinges 8, 9 and 10 all work the same way.

Desirably the seat 1 is attached to the support 5 in the knocked down as well as in the set up position. To accomplish this the seat 1 is joined to the support by a securing device 12, Figs. 3 and 5, which (1) allows the folding of the member 5 along the vertical axis $a-a$, while in addition permitting the seat to be folded against the member 5 when folded along the axis $b-b$, as shown in Figs. 3, 4 and 5; and (2) allows the seat to have a movement of translation, i. e., to slide with respect to the folded support 5 so as to allow the seat 1 to be centered with respect to the folded support 5, this sliding or translatory movement also being a desirable feature of the embodiment of Fig. 7 to be described.

I preferably accomplish these movements by constructing the attaching device 12 of a rod 14 which conveniently is an extension of the pin of hinge 8, said rod terminating in a portion bent at right angles and having a head 15, Figs. 5 and 6. The rod 14 secures the support 5 to the seat 1 by being engaged by a member 17, best shown in Fig. 6, secured to the portion 2 of the seat 1 as by screws 18 engaging eyes 19 formed in said member 17, the latter making a loop 20 around the rod 14. However, other hinges of universal type may be employed and if desired the seat may be separable from the support. When the seat is in set up position, as shown in Fig. 1, the sides of the member 5 are further secured to the seat 1 by means of clips 22—22 fastened to the member 2 of the seat 1, such clips engaging prongs 23 attached to support 5.

As seen from the drawings, desirably the axes $b-b$ and $c-c$ divide the member 5 into segments or panels of equal width, which width is substantially that of the seat 1, all as clearly shown in Figs. 2 and 3. Also the length of the seat is substantially equal to the length of the panel formed by the axis $b-b$ and when the dihedral angle is 180° ; also, the axes $b-b$ and $c-c$ divide the member 5 in substantially equal parts. If desired, and especially where a higher stool is required, the member 5 may be foldable along additional parallel horizontal axes, which folds are hinged so as to move in accordion fashion as in Fig. 3.

In the embodiment of Figs. 7 to 11 the seat 1, instead of being folded outside the support 5 as in the preceding embodiment, may be disposed within the folds of the support. In this case the support 5' is foldable along a single horizontal axis $d-d$, the seat 1' being shown without the

cushion of Fig. 1 (although this may be provided if desired), the hinges 1'-1' of the axis d-d permitting the support 5' to enclose the seat 1' as shown in Fig. 10, and to accomplish this said hinges 1'-1' have the leaves thereof bent at an angle as shown in Figs. 7 and 9, thereby offsetting the axis of said hinge the necessary amount to accommodate the thickness of the seat 1'.

Fig. 11 shows how the seat 1' may be slid with respect to the support 5' along the neck or rod 14' of the hinge rod 12', thereby to assume the position shown in Fig. 8 entirely within the fold of the member 5; it also shows how in setting up the stool the seat is moved to the dotted line position where it is above the top of the member 5'. The folds of support 5', when the device is knocked down, may be secured together by means of spring clip 25, Fig. 10, or other means not shown.

In order for the member 17 and the heads of screws 18 to clear the top edge of the support 5, the said edge is recessed at 26, 26, Figs. 5, 6 and 1 (26', Fig. 8). If desired the panels A and B may be locked in the set up position by means of a hook 27 attached to panel A and releasably engaging panel B, although ordinarily this hook or similar locking device is not needed, reliance being had upon the securing action of clips 22 and prongs 23.

From the foregoing it is believed that the operation of setting up and knocking down my improved stool will be readily apparent. Thus, in knocking it down the panels A and B of the support 5 are released from the clips 22 by spreading the same and the bending continued along axis a-a until the dihedral angle of 180° is reached, whereupon bending will be permitted along axes c-c and d-d and the seat folded against the folded support 5, all as shown in Figs. 3 and 5 for the first described embodiment, and Fig. 10 for the second embodiment in which the seat is enclosed within the panels of support 5'. In the first embodiment, it will be noted that when panels A and B are bent to exactly 180° angle, the prongs 23 may interfere slightly with the folding down of the seat 1. When the seat corners are rounded as in Fig. 1 this interference is minimized; if the corners are not rounded the bending of the panels can be continued slightly beyond the 180° value until the seat clears the prongs 23.

It will be seen from the foregoing that my improved device may be constructed of light, strong material, for example plywood, may be folded into small compass, e. g., approximately 5" x 10" x 2" for the embodiment of Fig. 1 (somewhat larger size for the embodiment of Fig. 7), and in such knocked down form may be readily carried in a brief case, under arm bag or a special carrying bag with shoulder strap if this is desired, where it may be available for use at excursions, games, crowded trains, etc., and the fatigue due to standing thereby avoided.

While I have illustrated and described in detail preferred forms of my invention, it is to be understood that changes may be made therein and the invention embodied in other struc-

tures. I do not, therefore, desire to limit myself to the specific constructions illustrated, but intend to cover my invention broadly in whatever form its principle may be embodied.

I claim:

1. In a portable folding stool, a seat, a support therefor comprising a flat generally rectangular member hingedly foldable along a vertical axis to form in supporting position two sides of a V-shaped trough, the seat in said position resting upon the top edges of the sides, said member being also hingedly foldable, when the dihedral angle between said sides is 180°, along a horizontal axis to form generally rectangular panels, means for attaching said seat to said support when said member is in supporting position, including means for universally hinging said seat to said support, said seat being of a shape and size so as to be substantially contained within the periphery of at least the largest of said panels whereby in knocked-down position said seat forms with said panels a series of flatwise superimposed leaves constituting a compact, easily packageable bundle substantially free from protruding parts, said universally hinging means permitting the parts so hinged to assume either erect or knocked down position without detachment from one another.

2. The stool according to claim 1 in which said panels are of substantially equal size.

3. In a portable folding stool, a seat, a support therefor comprising a flat generally rectangular member hingedly foldable along a vertical axis to form in supporting position two sides of a V-shaped trough, the seat in said position resting upon the top edges of the sides, said member being also hingedly foldable, when the dihedral angle between said sides is 180°, along a horizontal axis to form generally rectangular panels, means for attaching said seat to said support when said member is in supporting position, said seat being attached to said support by a universally hinging device which comprises a shank constituting the pin of a hinge between vertical folds of said member and a securing device attached to said seat and movably engaging said shank, said seat and said panels when collapsed constituting a compact, easily packageable bundle.

CLIFFORD D. KEELY.
